LE GRAND PARISH.

UNITED STATES PATENT OFFICE.

LE GRAND PARISH, OF MOUNTAINVIEW, NEW JERSEY, ASSIGNEE TO AMERICAN ARCH COMPANY, OF NEW YORK, N. Y., A CORPORATION OF DELAWARE.

LOCOMOTIVE-ARCH.

1,229,388.

Specification of Letters Patent. Patented June 12, 1917.

Application filed February 11, 1916. Serial No. 77,645.

To all whom it may concern:

Be it known that I, LE GRAND PARISH, a citizen of the United States, residing at Mountainview, Passaic county, New Jersey, have invented certain new and useful Improvements in and for Locomotive-Arches, of which the following is a specification.

My invention relates to improvements in refractory front arch constructions for locomotive-boiler fireboxes. The object of my invention is to improve the shapes, construction, and operation of the component bricks of such arches. A special object of the invention is to improve the form and construction of the so-called body-bricks of refractory arches; and to provide so-called marginal or side-bricks of improved form and construction for co-operation with such body-bricks.

The general characteristics of my invention as well as the details thereof will be readily understood on reference to the drawings that form parts of this specification, and in which Figure 1 is a longitudinal section of a locomotive boiler firebox equipped with a front arch embodying my invention; Fig. 2 is a sectional view of one of the body-bricks on the line X—X of Fig. 3; Fig. 3 is an enlarged transverse section disclosing a firebox side sheet, two water-circulating arch tubes and body and marginal bricks thereon; Fig. 4 is a vertical section of the bricks shown in Fig. 3; Fig. 5 is an inverted plan view of one of the arch-body-bricks, reduced in size; Fig. 6 is an end view of the body-brick; Fig. 7 is a similarly reduced inverted plan view of one of the marginal bricks; Fig. 8 is an inner end view thereof; and Fig. 9 is a detail showing a shift of position of the body-brick upon the arch tube.

Referring to Fig. 1 of the drawings, the lines which represent the grate of the firebox are marked 1; 2, is the rear sheet of the firebox; 3, is the flue sheet; 4, is the crown sheet; 5, the side sheets; 6, the door of the firebox; 7, an arch-tube; and 8, are the flues of the boiler. The water circulating arch-tubes, 7, extend longitudinally and are inclined in the firebox, and are spaced apart transversely therein. Between each two tubes, 7, there is a longitudinal row of body brick, A; and between the outermost row of body bricks and each side sheet, 5, there is a row of marginal bricks B.

The novel bricks, which primarily comprise my invention, are of shapes and constructions which give them adequate strength, which cause them to act properly and reliably with relation to one another, 60 and which cause them to firmly retain their positions upon their supports. They have the further characteristic of being reversible and invertible.

As all of the body-bricks, A, are of the same shape or form, a description of one will serve for all. Likewise, the marginal bricks, B, are all alike and a description of one will serve for all.

The over-all length of the body-brick, 70 A, is substantially the same as the distance between the centers of the arch tubes, 7, which support it. Each end of the brick, A, is formed with, or contains, a socket, a' , shaped to fit an arch tube, 7, in the manner shown. These sockets, a' , a' , are diagonally opposite one another in the brick so that one is presented upwardly in one end and the other downwardly at the other end. Directly opposed to each socket is an inclined portion, a^2 , the major part of which is straight (in the longitudinal section of the brick) while a minor or terminal position, a^3 , is curved, a sharp corner being avoided, for the purposes hereinafter explained. The top and bottom surfaces a^3 and a^4 , are parallel planes. In the wall of each socket, a' , I prefer to form a recess, a^5 , which terminates short of the sides of the brick and also terminates short of the end 90 of the brick. In this manner two bearing surfaces, a^6 , are provided to conform with the side and top of the arch tube and an extended edge-bearing, a^7 , is formed for engagement with the top of the tube. Usually 95 the brick will be both reduced in weight and increased in strength by the formation of recesses, a^8 , in one or both surfaces, a^4 , a^3 , as indicated by full and dotted lines in Fig. 4. These recesses are so formed as to 100 be substantially symmetrical, not in the brick itself, but with respect to an imaginary arch line, 9, springing from the centers of the tubes, 7. In this manner the thick central portion, a^9 , and the intermediate 105 thin portions of the brick are made to best coact to prevent fracture of the brick at the center. It will be noted that the parts, a^6 , provide two widely separated bearings for the socketed end of the brick upon its 110

arch tube. Such tubes are not always exactly regular and parallel and to the end that the bricks may rest firmly between its two tubes, I form it in manner to provide three points of bearing thereon; two upon one tube and one upon the other. The problem of providing these three points of bearing is very simply solved by transversely curving the inclined surfaces, a^2 , as indicated by full lines, in Fig. 3, and by the curved line, a^{2x} in the sectional Fig. 2. Obviously the contact between the curved surface, a^{2x} , and the supporting tube is limited to a substantially single point, a^2 . Very little curvature of the surface, a^2 , is required to accomplish this end. It will be clear that the body-brick is invertible upon the tubes, 7, and is also reversible, end for end, upon the arch tubes, 7. Its form allows it to act in one position as well as in the other.

For co-action with the side sheets, 5, of the fire-box and to occupy the space between the same and the adjacent body-brick, A, I provide a marginal brick, B, of the form well shown in Figs. 3, 4, 7 and 8. This brick is chiefly characterized by a semi-cylindrical inner end, b , proportioned to fit the socket, a' , of the body-brick, A. Obviously, the end shapes of the two bricks permit the marginal brick to assume various inclined positions with respect to the body-brick. This is required in order that the body-brick may automatically adjust itself to different spacings between the outer arch tube, 7, and the side sheet, 5. To facilitate such adjustment after the brick is in position and for the further purpose of making the brick invertible, I make the outer end of the brick, B, to conform to two semi-cylindrical surfaces, b^2 , b^2 , which meet at the middle of the brick, leaving a single point, b^3 , for engagement with the side sheet, 5. The body-brick is both lightened and strengthened by providing it with recesses, b^4 , in one or both sides. On the end of the brick, B, I provide a projection or stop, b^5 , of a length to be accommodated in the recesses, a^5 , in the socket of the body-brick. The lug or stop, b^5 , may be a single projection or may be divided into two parts, as shown in Fig. 7. I prefer the two projections as they permit the straddling of the brick, B, across the ends of two body-bricks, A, as indicated by dotted lines, 10, in Fig. 7. The office of the stop, b^5 , is to prevent the displacement of the brick, B, from the socket of the body-brick, and it performs this office in conjunction with the projections, a^6 , and also in conjunction with the ridge, a^7 . The bearing or ridge, a^7 , serves as a limiting stop for the narrow lug, b^6 , on the brick, B, and prevents the inner end thereof from slipping off the body-brick.

It will be noted that the end of the body-brick, A, which serves as an adjustable abut-

ment for the marginal brick, B, is freely slideable on the outer arch tube, 7, due to its inclined end. The opposite end of the body-brick is firmly abutted against the inner arch tube, 7. Any endwise movement imparted to the brick, A, by the warping of the inner arch tubes, 7, is obviously communicated to the marginal brick, B, which automatically adjusts itself against the side sheet, 7. And reversely, the inward movement of the marginal brick, B, is communicated to the body-brick, A, in abutment therewith. Such movements of the two bricks cause the same to rise and fall upon and with respect to the outer arch tube, 7. As long as the major straight portion, a^2 , of the inclined end, is in engagement with the side of the arch tube, there is slight danger of dislodgment or disarrangement on the tube, but, when the brick or the tube shifts its position in the manner depicted in Fig. 9, the danger is increased. Hence the provision of the curved surface on the end of the brick, A. This curved end allows the brick to settle and to more tightly wedge against the tube, 7, and thus counteract the breaking effect of the vibration of the brick on the arch tube and minimize the abrasive action of the brick upon the tube.

It will be found that fire bricks of the forms, A, and, B, are extremely strong, due to the disposition of the material in the manner shown;—which disposition insures the uniform baking or “firing” of the bricks in the kiln, and obviates the checking and cracking of the bricks during the firing process. The bricks are especially advantageous because they are free from sharp angled corners which are apt to be broken when the bricks are in transit or are being piled or otherwise handled.

A correct idea of the sizes of the bricks will be gained from the statement that even the large body bricks are of a size permitting them to be passed through the fuel door, 6, of the firebox.

Having thus described my invention, I claim as new and desire to secure by Letters Patent:—

1. A locomotive firebox arch-body-brick, having diagonally opposed socketed ends in combination with arch tubes supporting said ends, a firebox side sheet adjacent one of said tubes and a marginal brick having its inner end shaped to fit the opposed socket of the body-brick and held therein while its outer end rests against said side sheet, as and for the purposes described.

2. A locomotive arch-body-brick having diagonally opposed arch tube sockets in its ends and also provided with diagonally opposed inclined end surfaces, as and for the purposes described.

3. An arch-body-brick having diagonally opposed arch tube sockets in its ends and also

- provided with diagonally opposed inclined end surfaces, each said inclined surface being transversely curved, as and for the purposes described.
5. 4. An arch-body-brick having diagonally opposed arch tube sockets in its ends and also provided with diagonally opposed inclined end surfaces, each said socket containing a recess and each said inclined surface being transversely curved, as and for the purposes described.
5. An arch-body-brick having diagonally opposed arch tube sockets in its ends and also provided with diagonally opposed inclined surfaces, and a curved surface, α^* , merging each inclined surface with the respective extreme end of the brick, as and for the purposes described.
6. An arch-body-brick having diagonally opposed inclined ends and diagonally opposed arch tube sockets, the latter containing bearing-forming, stop-recesses, in combination with a marginal brick having a semi-cylindrical end to fit one of said sockets and provided with a projection or stop lug accommodated by the recess therein, as and for the purposes described.
7. An arch-body-brick having an arch tube socket in the upper corner of the outer end and containing a stop recess, in combination with a marginal brick having a part-cylindrical end fitting said socket and having a stop lug accommodated by the recess therein, as and for the purposes described.
8. A marginal arch brick having a semi-cylindrical inner end, and an outer end conforming to intersecting semi-cylindrical surfaces, as and for the purposes specified.
9. A marginal arch brick having a semi-cylindrical inner end provided with a stop lug or projection, as and for the purposes specified.
10. An arch-body-brick having diagonally opposed inclined ends and diagonally opposed arch tube sockets and provided with recesses, α^* , non-symmetrically positioned in the brick, as and for the purposes specified.
11. An arch-body-brick having an inclined wedging end comprising a straight portion, α^2 , and a curved portion, α^* , and said portion, α^2 , being transversely curved, as and for the purposes specified.

In testimony whereof, I have hereunto set my hand this 31 day of January, 1916.

LE GRAND PARISH.
